OPERATING AND LOCKING MECHANISM
FOR CANOPY DOORSRobert F. Rape, New Castle, Pa., assignor to The
Fleming Steel Company, New Castle, Pa., a
partnership

Application May 17, 1947, Serial No. 748,686

5 Claims. (Cl. 268—74)

1

This invention relates to apparatus for operating and locking doors, particularly large doors of the canopy type such as are installed in airplane hangars and the like. These doors tilt about a horizontal axis adjacent their upper edge.

Canopy doors for airplane hangars are large, unwieldy structures and the operation thereof presents peculiar problems. These doors may be from 20' to 75' high and 100' wide or more. They must be light enough to permit opening without overloading the building frame but must have sufficient rigidity to be self-sustaining and capable of withstanding heavy wind loads. These requirements call for special characteristics in the mechanism for operating the door from closed to open position and back.

Various forms of door-operating mechanisms have been proposed but none of those with which I am familiar is satisfactory in all respects. Most of the prior devices employ a rope and windlass for tilting the door. This form of mechanism leaves the door free and uncontrolled between fully open and closed positions so that it may be lifted by an updraft of air and then suddenly released. The door and its operating mechanism may thus be subjected to excessive overloads. The mechanisms provided for the purpose heretofore have thus failed adequately to meet the need and it is the object of my invention, therefore, to improve generally on previously known apparatus for operating canopy doors. A more specific object is to provide a door-operating mechanism which maintains positive control of the door in all positions and precludes undesired movement thereof as by wind forces. A further object is to provide automatic door-locking means effective after the door is closed to prevent it from being partly opened by wind pressure.

In a preferred embodiment of my invention, I provide a door leaf or panel with one or more main posts or stems extending beyond the upper edge thereof in the plane of the leaf. I employ a radius arm or strut for each post pivoted at one end on a common axis adjacent but offset from that of the door itself. The radius arms are disposed at an oblique angle to the door when the latter is in closed position and have guides for synchronizing rollers mounted on the posts. The radius arms have means traveling therealong for causing the synchronizing rollers to move along the guides, thus tilting the posts and the arms at the same time. The traveling means may conveniently be a loop of a flexible tension member such as a chain trained about sprockets adjacent the ends of each radius arm with its ends secured

5 to the post. A detent on the end of each post cooperates with a pin on the radius arm to lock the door in closed position. The detent and pin move into locking engagement automatically through the action of the synchronizing rollers as the door approaches its closed position.

A complete understanding of the invention may be obtained from the following detailed description and explanation which refer to the accompanying drawings illustrating a preferred embodiment. In the drawings,

Figure 1 is a vertical section through one-half of a building having the door of my invention installed therein and serving as one side wall of the building, the door being shown in elevation, looking from the interior;

Figure 2 is a horizontal section taken along the plane of line II—II of Figure 1, showing the door and operating mechanism therefor in plan;

Figure 3 is a vertical section taken along the plane of line III—III of Figure 1;

Figure 4 is an elevation of the radius arm showing the appearance thereof when looking from the right in Figure 3;

Figure 5 is a diagram showing the successive stages of movement of the detent and locking pin into and out of locking engagement; and

Figure 6 is a view similar to Figure 3 showing the door in partly opened position.

Referring in detail to the drawings, the door of my invention is adapted to constitute one wall of a building such as an airplane hangar. As shown in the drawings, the building comprises columns 10 and roof trusses 11 extending therebetween with sheathing 12 and roofing 13 applied thereto in any desired manner. The building is open at one side and the open side is adapted to be closed by a canopy door. The door indicated generally at 14 is composed of one or more panels 15 through 18 disposed side by side and secured together for movement as a unit. Supplemental panels 19 are disposed at each end of the row of main panels.

Each of the panels includes a lower leaf 20 and an upper leaf 21, the lower leaf being movable vertically on the upper leaf. For this purpose, the lower leaf has rollers 22 traveling along posts 23 forming part of the upper leaf and the upper leaf has rollers 24 along which travel posts 25 forming part of the lower leaf. The posts are simply beams extending upwardly from the leaves in the plane thereof. Hoisting ropes 26 secured to the lower leaf pass over sheaves 27 to drums 28 on a shaft 29. The sheaves 27 are journaled in brackets 27a extending inwardly

from the posts 23. The shaft 29 is operated by a motor drive unit 30 (see Figure 2) and has a counterbalance drum 31 adjacent each end of the building on which a counterweight 32 is suspended (see Figure 1). As shown in Figure 1, the posts 23 and 25 are disposed between adjacent panels, each panel being secured to the adjacent posts. The door as a whole is pivoted on a horizontal axis adjacent the upper edge thereof. Pivot bearings 33 carried by the roof truss above the door extend downwardly on each side of the posts 23 and pivot pins 34 extend through these bearings and the posts.

The shaft 29 is journaled in bearings secured to hangers 35 depending from girders 36 connecting adjacent roof trusses 11. A second shaft 37 is also journaled in bearings carried by the hangers 35. Radius arms 38 are pivoted on the shaft 37, each arm comprising spaced cam track channels 39 having guide tracks 40 on the adjacent faces thereof for synchronizing cam follower rollers 41 pivoted on the posts 23 adjacent the upper end thereof. As shown in Figure 4, the posts 23 extend between the channels of the radius arms. Idler sprocket wheels 42 are journaled on a pin 43 extending through the channels 39 adjacent their upper ends. Driving sprocket wheels 44 are keyed to the shaft 37. Chains 45 trained around the sprocket wheels 42 and 44 are dead ended on a terminal fitting 46 secured to the upper end of each post 23. When the door is in closed position, the pin 43 enters a detent 47 in the form of a notch in the end of the post 23 and locks the door against inward swinging movement as the result of external force such as that applied by wind pressure.

A motor drive unit 48 is provided for the shaft 37 (see Figure 2). When the lower leaf 20 has been lifted, it will be apparent that clockwise rotation of the shaft 37 will cause the door to tilt about the pivot pins 34, the upper ends of the posts 23 being moved clockwise by the downward pull on the upper run of the chains 45. The radius arms 38 are simultaneously moved clockwise by the cooperation of the synchronizing rollers 41 with the guide tracks 40. As shown in Figure 5, the pins 43 move away from the detents 47 and clear the upper ends of the posts 23 because of the spacing of the centers of rotation of the posts and arms.

Figure 6 illustrates in solid lines the intermediate position of the door and arms and, in chain lines, the fully opened position in which the door is almost horizontal. The shaft 37 is also provided with a counterbalance drum 49 (see Figure 2) from which counterweights 32 are suspended. When it is desired to close the door, reverse rotation of the shaft 37 effected by the drive unit 48 applies upward tension to the upper run of the chains 45, thereby causing the synchronizing rollers 41 to travel back along the tracks 40, swinging the arms 38 as they move therealong. As the door approaches vertical position, the pins 43 again reenter the detents 47 and thereby hold the door against inward swinging movement until the shaft 37 is again driven in clockwise direction. When the door has been restored to vertical position, the lower leaf 20 may be caused to descend by operating the drive unit 30 to turn the shaft 29 in the counterclockwise direction.

It will be apparent from the foregoing that the invention provides a door operating mechanism which maintains the tilting movement of the door under positive control at all times and a

door-locking mechanism which becomes effective automatically when the door reaches vertical position. There is thus no possibility of the door being lifted by a puff of wind as it is being opened or closed and no danger of swinging movement or vibrations of the door in closed position under variations in wind pressure. The construction of the operating mechanism is simple and presents no particular problem in construction or operation. The driving motors may be controlled by known interlocking means to insure the proper cycle of operations in both opening and closing directions.

The door is of sectional construction and may thus be designed for various widths. The fact that the operating mechanism positively controls the movement of the door at all times, permits the door to be constructed in widths as great as 120' or more without danger of excessive warpage or distortion from wind variations or unequal application of operating forces, during the opening and closing movements.

Although I have illustrated and described a preferred embodiment of the invention, it will be understood that changes in the details of construction may be made without departing from the spirit of the invention or the scope of the appended claims.

I claim:

1. Operating mechanism for a swingable door, comprising a structural member extending rigidly from the door, a rigid radius arm pivoted on a fixed support spaced laterally from the door, a wheel rotatably mounted on the free end of the arm and a wheel rotatably mounted co-axially with the pivotal axis of the arm, a flexible tension member extending around said wheels and having its opposite ends secured to adjacent portions of the door extension member, reversible driving means connected to the flexible tension member, said tension member being drawn taut to oppose swinging movement of the door in either direction while the flexible tension member is being driven to open or close the door, and a detent fixed to the free end of the radius arm and adapted to engage and stop the door extension member when the door extension member is drawn by the flexible tension member against the detent, thereby limiting movement of the door in one direction, transferring from the flexible tension member to the radius arm the burden of opposing air pressures tending to push the door beyond the limit controlled by the detent, and preventing the door extension from swinging so far along the free end of the radius arm as to disengage the flexible tension member from the wheel on the free end of the radius arm.

2. Operating mechanism for a swingable door, comprising a structural member extending rigidly from the door, a rigid radius arm pivoted on a fixed support spaced laterally from the door and having a cam track extending therealong, a wheel rotatably mounted on the free end of the arm and a wheel rotatably mounted co-axially with the pivotal axis of the arm, a flexible tension member extending around said wheels and having its opposite ends secured to adjacent portions of the door extension member, reversible driving means connected to the flexible tension member, said tension member being drawn taut to oppose swinging movement of the door in either direction while the flexible tension member is being driven to open or close the door, a cam follower secured to the door extension member and extending into and travelable along the cam

track in the radius arm, and a detent fixed to the free end of the radius arm and adapted to engage and stop the door extension member when the door extension member is drawn by the flexible tension member and is guided by the cam follower and cam track against the detent, thereby limiting movement of the door in one direction, transferring from the flexible tension member to the radius arm the burden of opposing air pressures tending to push the door beyond the limit controlled by the detent, and preventing the door extension from swinging so far along the free end of the radius arm as to disengage the flexible tension member from the wheel on the free end of the radius arm.

3. Operating mechanism for a swingably mounted door comprising a member integral with the door, a rigid radius arm pivoted on a fixed support spaced laterally from the door and having a cam track extending therealong, a cam follower carried by said door member and movable along said track, supporting means connected to the radius arm at opposite ends of the cam track, a flexible tension member movably trained around said supporting means and tautly fastened to said door member, and driving means connected to the tension member to draw it around said supporting means, whereby the driving means is connected to draw the cam follower along the cam track to swing the door while the tension member holds the door against air pressures on either side of the door in each successive position of the door.

4. Operating mechanism for a swingably mounted door comprising a member integral with the door, a rigid radius arm pivoted on a fixed support spaced laterally from the door and having a cam track extending therealong, a cam follower carried by said door member and movable along said track, rotatable wheels connected to the radius arm at opposite ends of the cam track, a chain looped around said wheels and tautly fastened to said door member adjacent the cam follower, one of said wheels being a sprocket wheel mounted coaxially with the radius arm, and a

reversible motor connected to drive said sprocket wheel to draw the chain around said wheels, whereby the motor is connected to draw the cam follower along the cam track to swing the door while the chain holds the door positively against air pressures on either side of the door in each successive position of the door.

5. Operating mechanism for a swingably mounted door, comprising a member integral with the door, a rigid radius arm pivoted on a fixed support spaced laterally from the door and having a cam track extending therealong, a cam follower carried by said door member and movable along said track, a reversible motor connected to drive the cam follower along the cam track, and means on the radius arm adjacent its free end and means on the door member adapted to be brought into abutting relation through the guiding action of the cam follower as it approaches the free end of the radius arm, whereby said abutting means lock the door against further movement beyond one extreme position and thereby relieve the driving means of the burden of holding the door against said further movement.
